UNITED STATES PATENT OFFICE.

AQUILINO R. VILA, OF HABANA, CUBA, ASSIGNOR TO COMPAÑIA CUBANA ECONOMIZADORA DE COMBUSTIBLE S. A., OF HABANA, CUBA, A CORPORATION OF CUBA.

HEAT-EXCHANGE APPARATUS.

Application filed October 25, 1924, Serial No. 745,796, and in Cuba October 2, 1924.

This invention relates to heat exchange apparatus especially adapted for use for heating water for feeding a steam boiler, or heating sugar juices in the manufacture of sugar, and its object is to provide an improved apparatus for effecting such heating by using the exhaust steam of steam turbines or engines to heat a plurality of heaters through which the water to be heated circulates, and thus effect a very important economy of fuel.

With the above and other objects in view the invention consists in the construction, combination and arrangement of devices hereinafter described and claimed.

In the accompanying drawings—

Fig. 1 is a side elevation of a heat exchange plant constructed and arranged in accordance with this invention.

Fig. 2 is a front elevation of the same.

Fig. 3 is a cross vertical section on line 3—3 of Fig. 1.

Fig. 4 is a longitudinal vertical section on line 4—4 of Fig. 2.

My improved heat exchange plant comprises a cylindrical or boiler shaped tank 1 designed to receive the liquid 2 to be heated. Said tank is mounted on two supports, one near each end, each support being formed of a pair of uprights 3 which are metal I-beams provided with widened bases 4 formed by angular plates, the two uprights of each pair being connected together by a metallic segment shaped piece 5, entering under the tank 1, one upright of a pair being connected to one upright of the other pair, at each side of tank 1, by a horizontal I-beam 6 connected thereto by angular pieces 7 and which is reinforced by braces 8 which are also metallic angular cross section pieces. Tank 1 is of a construction similar to that of inner furnace boilers, and has a cylindrical body 9 which is eccentric with respect to the outer jacket and which projects at its ends beyond the same, the cylindrical body 9 being secured to the heads by flanged collars 10. The interior of said cylindrical body 9 is occupied by two groups of liquid tubes 11 and 12, whose ends are closely fitted in openings formed in vertical plates 13 and 14 which form the heads of said cylindrical body 9, and which are secured in position on the ends of the cylindrical inner body 9 by means of flanged collars 15 and 16 respectively.

A semi-spherical hollow cap 17 is secured on the outer side of the head 13 and affords communication between said groups of tubes. A cap 19 is secured on the outer side of the head 14 and is provided with a straight short pipe 20 and a curved tube or elbow 21. The pipe 20 is connected to a U-shaped tube 22 which leads from the outlet of a pump 24 and is provided with a valve 23 as shown. Said pump is mounted on frame 25 connected to one of the supports 3. The intake of said pump 24 is connected by tube 26 which has a valve 27 with a tube 28 which leads to the bottom of the boiler. A tube 29 also leads from the tube 26 and has a valve 30.

The curved tube 21 is connected through a tube 31 and an elbow 32 with a group of tubes 37 which are arranged in a cylinder 36 substantially identical with the cylinder 9. Said cylinder 36 also has a group of tubes 38 and heads 35 39 through which the ends of the tubes 37, 38 extend. A hollow semi-spherical cap 42 is secured on the outer side of head 39, said head being secured to an angle collar 41 and the head 35 being secured to an angle collar 40. A tube 34 leads from one end of the group of tubes 38. The cylinder 36 is arranged above the boiler 1 and is supported on the upper ends of tubes 43 which rise from the boiler and are connected thereto at 44, 45 respectively. One of said tubes has a branch 46 for the intake of a supply of liquid to be heated and the other has a branch 47 for outlet of steam from the boiler. A man hole cover 49 closes an opening 48 in the top of the boiler.

The exhaust steam from the steam turbines or engines reaches the plant through a horizontal tube 50 which by means of a cross-fitting 51 is connected to two vertical branches 52 and 53 which are united by a T with a short vertical tube 55 which discharges in an opening formed in cylinder 9 at its projecting end outside boiler 1. From the cross fitting 51 leads another tube 56 to a safety valve 58 which through a short vertical tube 59 connects with an inlet 60 formed at the center of the length of the outer cylinder 36 so that it may cause the exhaust steam from the steam turbines or engines to pass directly into said cylinder.

The plant is provided with a water gauge 61 which is connected to a close metal ver-

tical tube 62, which is connected in turn by a lower branch 63 to the body of boiler 1 at its lower part and by an upper branch 64 to another tube 64' which leads upwardly from the body of cylinder 36 and is provided with a pressure gauge 65.

In this apparatus the liquid to be heated enters at the atmospheric temperature in tank 1 through tube 46 and annexed supporting conduit 43, and from the tank is forced by the pump 24 through tubes 26 and 28, which pump injects the liquid of tank 1 into the heater 9 in the interior of said tank, causing liquid to pass previously from one to the other end through the lower bunch of liquid tubes 11 and then reversely through the liquid tubes of the upper bunch 12, during which movement the said liquid is heated by the exhaust steam which fills cylinder 9 and which has entered through the tube 55 that communicates with the vertical tubes 52 and 53 which in turn communicate with inlet tube 50 for the exhaust steam. The liquid in tank 1 has been also heated previously to its entrance into the heater 9 through the heat radiated to the mass of liquid of tank 1 by the cylindrical body 9 which crosses the mass of liquid and whose interior is charged with exhaust steam. The hot liquid coming from the bunch of tubes 12 is directed upwardly by the proper pressure of pump 24, passing through tubes 21, 31 and 32, and entering into the bunch of liquid tubes 37 of heater 36 at the exterior of tank 1 for passing from one to the other end of cylinder 36 and thence reversely through the upper bunch of liquid tubes 38, during which movement said liquid is heated to its maximum degree by the heat transmitted to liquid tubes 38 and 37 by the exhaust steam which occupies the cylinder 36. In the drawings are indicated three draining tubes, namely a tube 66 connected to the bottom of boiler 1 for the water in the latter, another tube 67 connected to the inner heating cylinder 9 for the condensation of steam therein and another tube 68 connected to the outer heating cylinder 36 for the condensation of steam therein.

The method of heating a liquid by this apparatus, whether such liquid be water to be fed to a steam boiler, or a sugar solution previous to its concentration, or any other liquid, consists in causing the liquid of a tank or boiler of low pressure to circulate

through the tubes of a heater 9 longitudinally arranged across the tank from one to the other head of the same, and by contact with which heater the mass of liquid of the tank is also heated. To the interior of said heater the exhaust steam of steam turbines or engines is carried. The hot liquid coming out of said heater circulates through the tubes of the second heater 36 arranged exteriorly of the tank and to the interior of which the exhaust steam of the steam turbines or engines also reaches.

While I have herein shown and described a preferred form of my invention, I would have it understood that changes may be made in the form, proportion and construction of the various parts within the scope of the appended claims.

What I claim is:

1. A heat exchange apparatus which comprises a tank adapted to receive a supply of cold liquid to be heated, a tube heater longitudinally arranged throughout the lower part of the tank, a second tube heater arranged outside the tank means for admitting a heating fluid to the space around the tubes of each heater, a pipe connecting the outlet from the tubes of first heater to the inlet to the tubes of the second heater, and a pump interposed between the tank and the first heater to cause the cold liquid from the tank to circulate first through the tubes of the heater inside the tank and then through the tubes of the heater outside the tank.

2. A heat exchange apparatus which comprises a tank adapted to receive a supply of cold liquid to be heated, a tube heater longitudinally arranged throughout the lower part of the tank, a second tube heater arranged outside the tank, a supply tube for exhaust steam communicating with the space around the tubes of each heater, a pipe connecting the outlet from the tubes of the heater inside the tank to the inlet to the tubes of the heater outside the tank, and a pump interposed between the bottom of the tank and the inlet to the tubes of the heater inside the tank to cause the cold liquid from the tank to circulate from the tank through the tubes of the heater inside the tank, and then through the tubes of the heater outside the tank.

In witness whereof I affix my signature.

AQUILINO R. VILA.
